The ornamental design for a rake moulding, as shown and described.

DESCRIPTION

FIG. 1 is a rear perspective view of a rake moulding showing our new design;

FIG. 2 is a rear elevational view thereof;

FIG. 3 is a front elevational view thereof;

FIG. 4 is a left side view thereof, the right side view being a mirror image thereof;

FIG. 5 is a top plan view thereof; and,

FIG. 6 is a bottom plan view thereof.

The rake moulding is shown with a symbolic break in its length. The appearance of any portion of the rake moulding between the break lines forms no part of the claimed design.
